UNITED STATES PATENT OFFICE

2,546,822

COMBINATION ROLLER TOY

Percy H. Herrick, Baltimore, Md., assignor to
Products Manufacturing Co., Inc., a corpora-
tion of Maryland

Application November 15, 1948, Serial No. 60,158

1 Claim. (Cl. 280—7.15)

1

This invention relates to vehicles and more particularly to those intended for the use of children and propellable by them.

It is an object of this invention to provide a new and improved vehicle that will avoid one or more of the disadvantages and limitations of the prior art.

Another object of the present invention is to provide a new and improved vehicle that can be adjustable to the convenience of the user.

A further object of the invention is to provide a new and improved vehicle for children that can be easily and interestingly operated by the user, and at the same time be safe in operation, simple in structure and have an attractive appearance.

Other objects will become apparent as the invention is more fully set forth.

For a better understanding of the invention and the objects thereof, reference is made to the attached drawings, which indicate a particular form of the invention by way of example. These drawings in conjunction with the following description outline the structure in detail, explain its operation and make its principles evident, while the claim added thereto emphasize the scope of the invention.

Referring to the drawings:

Figure 1 is a side elevation of a vehicle embodying this invention, with the connecting rod attached to the crank and seat;

Figure 2 is a plan view of Figure 1;

Figure 3 is an elevation of the device looking at it from the rear; and

Figure 4 is a side elevation of the vehicle shown in Figure 1, with the rod attached to the yoke to hold the seat stationary.

Similar reference characters refer to similar parts throughout the drawings.

In the particular construction shown in the drawings, a roller toy consists of a front steering wheel 10 for guiding the vehicle. It is mounted on a fork 11 leading to a straight shank 12 and spread handle bars 13. These handle bars have a conventional form and include the usual items for adjusting the handles in the shank 12, and the fork 11 supports the wheel bearings. A collar 14 of cylindrical form engages the shank 12 and is arranged to revolve horizontally on it. A fitting 40 extends rearwardly into a tubular frame 15 that bifurcates at 41 at the rear in a slantingly depending manner to form journaled termini 16 for supporting a rear axle 17. The rear axle 17 supports two wheels 18 and is bent at its middle portion to the contour of a crank member 19.

2

The crank member 19 is formed to enable a connecting rod 20 to be attached to and journaled on it. This connecting rod 20 is formed with an end eyelet 21 journaled in a bearing 22 attached to the underside and rear of an elongated seat board 23. A bracket 24 also rigidly attached to the underside of the seat board 23 is journaled in a bearing 29 on the frame 15 so the board seat may operate pivotally thereon about a vertical axis. This bracket 24 is preferably located adjacent the middle of the seat.

Foot rests 25 are provided for coasting and are rigidly extending forwardly from the underside of the seat 23 on an adjustable U-like bracket 31, and spread apart to position themselves on both sides of the front wheel 10 to enable the user to place his legs and feet towards the front of the vehicle. The bracket 31 is attached to the seat 23 by a bearing 43. However the seat 23 has two actions. It may stay in a rigid horizontal position, or by a slight adjustment be arranged to rock on its pivoting bracket 24 on its longitudinal axis. The connecting rod 20 has its free end portion made into a U-member 30 adapted to straddle the crank 19 so it can be fastened thereon by a sliding pin 28.

When the connecting rod 20 is brought forward so as to be attached to the yoke 27 under the frame 15, it acts as a rigid strut to prevent the seat from rocking up and down, and thereby keeps it stationary. However, by loosening the member 30 the yoke 27 may be swung backwards and mounted on the axle crank 19 so the member 30 is connected loosely to it, and the connecting rod 20 can be actuated by the seat becoming operable in a rocking movement. As the user moves the vehicle forward by pushing away from the ground with his legs, the connecting rod 20 is oscillated by the rear wheels 18 which propel the vehicle along the roadway. The user therefore has two ways in which to use this device, according to how he feels in the matter. The swinging position of the connecting rod 20 enables this to be done, and the effort required to arrange it is very small and can be easily performed. When the seat is in the stationary or rocking position, the user can ordinarily employ the efforts of his legs and feet to the ground to propel the vehicle.

While but one general form of the invention is shown in the drawings and described in the specifications, it is not desired to limit this application for patent to this particular form, as it is appreciated that other forms of construction could be made that would use the same principles

and come within the scope of the appended claim.

Having thus described the invention, what is claimed is:

A vehicle comprising a tubular frame having a horizontal front portion, a straight shank rotatively supported in the forward end of said frame, said shank having handle bars at its upper end and a fork at its lower end, a steering wheel mounted in said fork, said frame terminating in a bifurcated end extending downwardly from the aforesaid front portion, a crankshaft mounted in said bifurcated end, a pair of traction wheels secured to each end of said shaft, a seat, a bearing carried by said frame at the junction of the front portion and bifurcated end of the frame, a U-shaped bracket having the free ends of its side arms secured to the underside of said seat and having its horizontal portion rotatively received in said bearing, a pair of foot rests secured to the front end of the seat and extending downwardly therefrom to straddle the steering wheel, a yoke depending from said frame at a point in

vertical alignment with said bearing, and a rod having one end pivotally connected to the rear end of said seat and having its opposite end selectively connectible to either the said crankshaft or the said yoke, whereby said seat may be gyrated simultaneously about said bearing and crankshaft when said rod is connected to said crankshaft, and is immobilized with respect to said frame when said rod is connected to said yoke, said seat remaining horizontal when the rod is in said last position.
